UNITED STATES PATENT OFFICE.

BENJAMIN OSHMAN AND DAVID OSHMAN, OF NEW YORK, N. Y.

NURSING BOTTLE.

Application filed January 14, 1927. Serial No. 161,058.

This invention relates to nursing bottles, and its principal object is to provide a safety, sanitary, efficient, and improved nursing bottle.

5 Heretofore, the rubber nipples of nursing bottles were attached to the bottle-necks by merely stretching and slipping the nipple over the neck, and while doing so the user's fingers often deposited germs upon the 10 interior side of the nipple, with consequent danger to the infant's health. Those nipples also frequently slipped off the bottle-neck during the feeding, thereby causing annoying spillage, spoliation, wastage, and depriving the infant of food. Foreign substances and impurities often found in milk, 15 frequently entered the nipple and were taken up by the feeding, with consequent injury to the infant. Upon removal of the nipples and 20 cleansing of the bottles, the latter were frequently left open, through lack of sealing means, and gathered germs prior to refilling of the milk.

Among the objects of this invention, therefore, is the provision of means for remedying the above mentioned disadvantages.

Other objects and advantages will herein-after appear.

In the accompanying drawings,—

30 Fig. 1 shows a nursing bottle of this invention, with the improvements thereof shown in cross-sectional elevation.

Figs. 2 and 3 are cross-sectional elevations showing modifications of the improvements.

35 The usual nursing bottle 1 is provided at the extremity of its neck 2 with a threaded portion 3. The nipple 4 is made of the usual molded rubber film 5, the lower portion 6 of which is slipped over and firmly cemented to a nut 7 made of any suitable material, such as hard rubber, glass, celluloid, or composition. Said nut is provided with a tap 8 which may be threaded over the neck-extremity 3 in the manner shown, and 40 it may be threaded firmly against a gasket 9 which surrounds the threaded extremity 3 and rests upon an annular shoulder 10 that forms part of the glass bottle-neck and is located at the base of the threaded extremity 6. The nut 7 is provided with a central 45 tapped hole 11 into which threads the terminal 12 of a tubular strainer 13 provided with a plurality of fine perforations 14, whereby

when the nipple is in the mounted state shown the strainer projects downwardly into 55 the bottle-neck 2.

When using this nursing bottle, the infant feeds at the nipple 4 in the usual manner, and the milk filters through the strainer 13 before entering the nipple and is thereby fed 60 without danger of contamination which might result from possible impurities of the milk. As the nipple is directly cemented to the nut 7 and the latter is in turn screwed to the bottle-neck, any possibility of the nipple accidentally slipping off from the neck is precluded. The threading of the nipple-nut 7 against the gasket 9 produces a firm 65 closure of the bottle, and any possible leakage is prevented. It will be noted that the 70 provision for detachment of the strainer 13, by unthreading it from the nut 7, permits thorough sterilization of all the parts, as is regularly required for nursing bottles.

According to the modification shown in 75 Figs. 2, 3, the bottle-neck 2 is provided at its extremity with an additional threaded portion 15 which is of smaller diameter than the threaded portion 3 which receives the nipple, and the strainer 13 is provided with 80 a hollow tapped flange 16 which treads over the portion 15, thereby securing the strainer to the bottle instead of to the nipple, as was shown in Fig. 1. The nut 7 to which the nipple is cemented is threaded over the portion 3 and against the gasket 9 in the manner described in connection with Fig. 1. The tubular shell of the strainer 13 projects above the flange 16, forming the portion 17 which is threaded. When the nursing bottle with 85 all of its parts are sterilized and the nipple is stored away, a cap 18, Fig. 3, may be threaded over the portion 17 in the manner shown, and the bottle may be thereby effectively sealed and its interior maintained in 90 cleansed sterilized state until needed for further use.

Variations may be resorted to within the scope of the invention, and portions of the improvements may be used without others.

Having thus described our invention, we claim—

1. A nursing bottle having a neck, a thread on said neck, a nipple therefor having a threaded nut adapted to engage said thread, and said neck having an additional thread, and 105

a threaded perforated strainer engaging said latter thread and extending into the bottle.

2. A nursing bottle having a neck, a thread on said neck, a nipple therefor having a threaded nut adapted to engage said thread, said neck having an additional thread, a threaded perforated strainer engaging said latter thread and extending into the bottle,

said strainer having a threaded portion, and a cap threading over said portion. 10

Signed at the city of New York, in the county of New York, and State of New York, this 12th day of January, A. D. 1927.

BENJAMIN OSHMAN.
